Benjamin P. Mann

UNITED STATES PATENT OFFICE.

SALVADOR C. FARINA, OF WEST NEW YORK, NEW JERSEY.

AIRSHIP.

1,408,873.

Specification of Letters Patent.

Patented Mar. 7, 1922.

Application filed May 18, 1921. Serial No. 470,594.

To all whom it may concern:

Be it known that I, SALVADOR C. FARINA, a subject of the King of Italy, and resident of West New York, in the county of 5 Hudson and State of New Jersey, have invented certain new and useful Improvements in Airships, of which the following is a specification.

This invention relates to improvements in 10 airships, and its principal object is to provide means that will prevent rapid descent or undue falling of the airship, in case any accident occurs thereto which renders its sustaining elements inoperative or power- 15 less. The invention is particularly adaptable for use in connection with aeroplanes, wherein the sustaining power is derived from the speed or propulsion of its carrying planes through the air, so that in case 20 any accident occurs to its propelling mechanism the entire machine often falls to the ground, which frequently results in its injury or destruction or in injury or death to its occupants.

25 Other objects and advantages will hereinafter appear.

In the accompanying drawings,

Fig. 1 shows a diagrammatic side elevation of an aeroplane which is equipped with 30 these improvements, and shows the latter in operative condition.

Fig. 2 is a front elevation of the aeroplane and improvements shown in Fig. 1.

Fig. 3 is a side elevation of the upper 35 carrying plane of the aeroplane, showing the invention in inoperative state.

Fig. 4 is an enlarged sectional plan view 40 of the middle portion of the fuselage of the aeroplane shown in Figs. 1, 2, and shows the operating mechanism of this invention.

The aeroplane 1 comprises the usual fuselage or directive body 2, upper and lower carrying planes or aerofoils 3, 4, front and rear struts 5, 6, bracing wires 7, rudders 8, 45 9, propelling motor or engine 10, gasoline supply tank 11, motor batteries 12, propeller 13, landing gear 14, and landing spur 15.

On top of the upper plane 3 is located 50 a bag or balloon 16 which normally lies thereon in collapsed state, as shown in Fig. 3, and to the sides of the balloon is secured a pair of planes 17, which, when the balloon is in collapsed state, lie thereupon in the 55 manner shown in Fig. 3. Said balloon and

planes 17 are maintained against lateral or other dislocation, relatively to the carrying plane 3, by means of dogs 18, hinged at 19, being pressed against the planes 17 by springs 20 that are secured to the planes 60 3 and to extensions 21 forming part of the dogs 18. The balloon 16 and planes 17 may be made of any suitable material, of which such parts are usually constructed, as is well known to those versed in this art. To 65 the planes 17 are secured series of cables 22 at 23, which are in turn secured to the carrying plane 3 at 24.

A flexible pipe or base 25 is connected to the balloon 16 at 26, from where it extends 70 downwardly, passes through the plane 3, and into the fuselage 2, whereat it is joined to a valve 27 connected to a union 28 that is connected to a pair of tanks 29, which are filled with compressed air or preferably 75 with some other compressed light gas such as is used for inflating balloons. Between the tanks 29 is located a pump 30 which is driven by a motor 31 that is fed from the gasolene tank 11 and is supplied with current for ignition and operation of its starting device 31^a by the batteries 12. An operating lever 32 is pivoted to the floor of the fuselage 2 at 33, and a chain 34 secured to said lever passes around a pulley 35 to 80 a point 36, whereat it is joined to a pair of chains 37 that pass around pulleys 38 and extend in opposite directions and are secured to extensions 39 that form part of the dogs 18. To the lever 32 is pivoted an 85 operating bar 40, to which are in turn pivoted an operating lever 41 for the valve 27, a lever-switch 42 for the engine starting-device 31^a, and an operating lever 43 for a valve 44 connected to a pipe 45 which 90 feeds the gasolene from the tank 11 to the motor 31.

Normally, the balloon 16 and planes 17 are disposed in the collapsed assembled condition, as shown in Fig. 3, and the aeroplane 100 can be operated and utilized in the regular manner. Should there occur an accident during flight, such as the stoppage of the engine or some injury or mishap to the propeller or other vital part of the machine, 105 which would cause the aeroplane to fall, the operator or other occupant of the same may pull and swing the lever toward the right, as viewed in Figs. 1, 4; and thereupon the chains 34, 37 will be drawn and cause the 110

dogs 18 to swing about their pivots 19, contrary to the pressure of the springs 20, and thereby release the planes 17. Simultaneously, the lever 32 will shift the operating rod 40 toward the right, which will thereby swing the operating levers 41, 43 and switch 42 to open the valve 27 and to feed the gasoline and electric current for the starting device 31^a and engine 31 to drive the pump 30. The compressed air or gas in the tanks 29 will then enter and inflate the balloon 16 through the pipe 25, and simultaneously the pump 30 will operate to feed additional compressed air to the balloon, whereby the latter will rise, above the plane 3 and the machine, and cause its planes 17 to open up and extend in the operative position shown in Figs. 1, 2, with the cables 22 securing the planes 17 and balloon 16 to the machine, in the manner shown. The balloon 16 and planes 17 being thus disposed in the inflated and operative condition they will constitute auxiliary sustaining means for the aeroplane, which will prevent it from rapidly falling to the ground and thereby save the machine and its occupants. It will be noted that when the balloon and auxiliary planes 17 are in inoperative state 30 and secured to the carrying plane 3 they lie lengthwise thereupon, but when in the operative state, Figs. 1, 2, they are disposed rightangularly to the carrying planes and parallel to the fuselage 2, in which manner they tend to buoy up and sustain the machine in perfect equilibrium when they are in operative condition, while they do not in any way interfere with the operation of the aeroplane when they are in assembled inoperative state. When the machine is finally landed upon the ground and rendered fit for further flight, the balloon and auxiliary planes 17 may be again readily reassembled into inoperative condition and the aeroplane may be thus restored for further service.

It will be clearly evident to those versed in this art that although the invention and improvements are here illustrated and shown as being utilized in connection with an aeroplane, the means and principles underlying the same may be well utilized in connection with any other kind of aerial vehicle.

55 Variations may be resorted to within the scope of the invention, and portions of the improvements may be used without others.

Having thus described my invention, I claim:—

60 1. In combination with an airship, means to prevent accidental rapid descent thereof including a balloon which is in collapsed state during flight, an airplane which is in inoperative state during flight, means containing compressed fluid, means to permit

said fluid to enter and inflate said balloon, and said balloon actuating said airplane into operative state.

2. In combination with an airship, means to prevent accidental rapid descent thereof including a balloon which is in collapsed state during flight, a pair of airplanes secured to said balloon, one at each side thereof, and in inoperative state during flight, means containing compressed fluid, means to permit said fluid to enter and inflate said balloon, and said balloon actuating said airplane into operative state.

3. An aeroplane having provision to prevent accidental rapid descent thereof including a balloon which is attached to its carrying plane in a collapsed state during flight, an auxiliary sustaining plane which is connected to its carrying plane in an inoperative condition during flight, means containing compressed fluid, means to permit said fluid to enter and inflate said balloon, and said balloon actuating said sustaining airplane into operative state.

4. An aeroplane having provision to prevent accidental rapid descent thereof including a balloon which is attached to its carrying plane in a collapsed state during flight, a pair of auxiliary sustaining planes which are connected to its carrying plane, one at each side of said balloon, and in inoperative state during flight, means containing compressed fluid, means to permit said fluid to enter and inflate said balloon, and said balloon actuating said auxiliary sustaining planes into operative state.

5. An aeroplane having provision to prevent accidental rapid descent thereof including a balloon which is attached to its carrying plane in a collapsed state during flight, a pair of auxiliary sustaining planes which are connected to its carrying plane, one at each side of said balloon, and in inoperative state during flight, means to maintain the balloon and said auxiliary planes to the carrying plane in the inoperative state, means containing compressed fluid, means to permit said fluid to enter and inflate said balloon, said balloon actuating said auxiliary sustaining planes into operative state, and means to release said maintaining means when permitting the fluid to enter the balloon.

6. In combination with an airship, means to prevent accidental rapid descent thereof including a balloon which is in collapsed state during flight, a tank containing compressed fluid being connected to said balloon, a pump connected to said tank, means to operate said pump, and means adapted to control said last means and to simultaneously open the connection between said tank and balloon to permit the fluid from said tank and pump to enter the balloon.

7. In combination with an airship, means

to prevent accidental rapid descent thereof including a balloon which is in collapsed state during flight, an airplane which is in inoperative state during flight, a tank containing compressed fluid being connected to said balloon, means adapted to open and close said connection to permit said fluid to enter and inflate said balloon, and said balloon actuating said aeroplane into operative state.

8. In combination with an airship, means to prevent accidental rapid descent thereof including a balloon which is in collapsed state during flight, an airplane which is in

inoperative state during flight, a tank containing compressed fluid being connected to said balloon, a pump connected to said tank, means to operate said pump, means adapted to control said last means and to simultaneously open the connection between said tank and balloon to permit the fluid from said tank and pump to enter the balloon, and said balloon actuating said airplane into operative state.

Signed at the city of New York, in the county of New York, and State of New York, this 13th day of May, A. D. 1921.

SALVADOR C. FARINA.
